METHOD OF REPAIRING DAMAGED SPOTS
IN FABRICSMary Louise Roach, Green Township, Hamilton
County, Ohio

Application November 4, 1940, Serial No. 364,255

8 Claims. (Cl. 2—243)

This invention relates to a method of mending fabric material, and in particular, woven fabrics, utilizing for the damaged portion a patch of the same material as that of the article being mended.

An object of the invention is to provide a method for mending the damaged portion of a woven fabric in a simple and expeditious manner to produce an invisible and secure mend comparable to an artisan performed interweaving or darning method of patching, generally too costly for the repair of garments or most grades of materials.

Another object of the invention is to provide an invisible and secure patch mending of a damaged portion of woven fabric by utilizing a rectangular section of cloth of the same material as that being mended, and applying the patch section without the use of an adhesive or other type of backing layer to avoid stiffening the mended area, and to have the warp and woof threads of the patch threaded through and extended to the reverse side of the fabric about the damaged portion.

Various other features and advantages of the invention will be more fully apparent from a description of the accompanying drawing, in which:

Figure 1 is a perspective view of a portion of the fabric with a damaged section cut out on lines parallel with the warp and woof threads, and a line of stitching applied marginally about the opening, binding the threads prior to applying the patch thereover.

Figure 2 is a plan view of the patch, preferably of the same material as the fabric.

Figure 3 is a plan view of the face side of a portion of the fabric with the patch in place preparatory to securing it to the fabric.

Figure 4 is a sectional view showing the free threads to the patch drawn through the fabric.

Figure 5 is a view similar to Figure 4, showing the marginal edge of the opening frayed, with the frayed edges of the patch and fabric secured together by a line of stitching.

Figure 6 is a view similar to Figure 4, showing the finished patch with the frayed edges thereof pressed flat.

Figure 7 is a plan view of the under side of the fabric, showing the completed patch.

Figure 8 is an enlarged sectional view showing as a modification a method of securing the patch by means of concealed cross stitching applied marginally about the adjoining edges of the patch and fabric.

Figure 9 is a view similar to Figure 8, showing a further modification in the method of securing the patch.

In practicing the invention, the fabric 1 about 5 the damaged spot or portion to be mended is cut out, as shown in Figure 1, to provide a rectangular opening or cut out area 2, the lines of the cut or edges forming the opening relatively extending parallel with either the warp or woof threads 10 of the fabric to permit the threads lying parallel with an edge to be ultimately frayed out to have the transverse threads extend out loosely.

A line of preferably small length stitching 3 is extended marginally outward about the rectangular opening to completely surround the same. The stitching binds the warp and woof threads of the fabric to prevent undue fray or ravel of the threads, and to provide a guide and matching line for the outer exposed area of a 20 patch 4, along which the loosely protruding warp and woof threads for the relative edges of the patch are threaded or drawn through the fabric to underlie the same.

The patch 4 is of rectangular outline and 25 slightly larger in dimension for area than the rectangular opening 2, and of the same material as that of the fabric. As shown in Figure 2, the patch provides a body portion of an area approximately corresponding to the space within 30 the boundary of the rectangular line of stitching 3 in the main fabric. The rectangular body of the patch is placed with its warp and woof threads relatively parallel or in registry with the threads of the main fabric surrounding the rectangular line of stitching, so that an absolute matching can be effected at the patching or meeting lines of the parts.

The margins of the patch are frayed so that 35 the patch constitutes a central body portion surrounded by free threads 5 constituting the loose extensions of the warp and woof threads of the patch section, leaving a body area of approximate dimension as represented by the area within the rectangular line of weave thread reinforcement 45 forcing stitching 3, preliminarily executed about the cut opening in the fabric being mended.

The patch in this instance being shown as square and the loose and free fibers or threads being constituted by omitting on opposite sides 50 of the body a number of the warp threads, and similarly omitting on the other sides of the body the woof threads, the loose threads or strands constitute the connecting or fastening means of the patch. The patch is placed over the outer 55 side of the fabric, as shown in Figure 3, with its

body edge abounded by the rectangular line of stitching, and with the pattern of the parts in matching assembly. The body of the patch is temporarily tacked or basted to the margins of the fabric about the opening to hold the same in place during the remaining operations.

The loose free threads 5 present a soft but efficient means for securing the patch to the fabric. The free threads entirely surround the body portion of the patch; the warp threads being at directly opposite edges of the patch, and the woof threads at right angles thereto at the other opposite edges of the patch. The threads are of a length most suitable to draw through the fabric and slightly overlap the underside thereof. The loose threads are individually drawn through the fabric from the face side thereof, and directly along and about the rectangular line of stitching 3 to extend from the underside of the fabric, as shown in Figure 4. This is readily accomplished, manually by means of a hooked needle engaged through the fabric from the underside to catch a thread and draw the same through the fabric, or power driven means having a special type of reciprocating needle acting from the face of the fabric for pushing the threads through the fabric. The means employed for drawing the threads through the fabric is optional, and to a degree dependent upon the kind of fabric being mended.

After the threads of the patch have been drawn through the fabric, the margin of the fabric at the inner side of the rectangular line of stitching 3 and the protruding fringe margin of the patch are bound together by a line of stitching 6, shown in Figure 5, extending as close as possible to the base of the margins, which combines the same as a hem at the underside of the fabric and patch.

The threads of the patch being drawn through the fabric at the outer side of the rectangular line of stitching extends the same through a firm portion of the fabric, which is reinforced by the line of stitching 3. After the hem has been stitched, a portion of the margin of the fabric is frayed similarly to the patch to remove from opposite sides a portion or number of the warp threads outwardly from the line of stitching, and similarly remove from the other opposite sides the woof threads.

The loose free threads of both patch and fabric present a soft, smooth surface upon their reverse side of the mended portion to avoid effecting any stiffening to the mended portion. The frayed or fringed margins 5 of the patch, after the threads thereof have been drawn through the fabric about the line of stitching and after stitching to the margin of the fabric within the line of initial stitching are pressed down to lie parallel with the fabric. The mend from the face side of the fabric is invisible, and the patch is strongly secured to the fabric and cannot be loosened or opened up under any strain that the fabric ordinarily may be subjected to or capable of withstanding. The method can be very expeditiously practiced by a dry cleaning establishment and at an exceedingly low cost.

As shown in Figures 8 and 9, as a modification of the method, the patch may be secured by means of a line of concealed cross stitching 7 applied marginally about the adjoining edges of the patch and fabric. The cross stitching is of zigzag form, embedded within the body of the fabric for concealment, and serves to draw the edges of the patch into close contact with the adjoining edges of the fabric. The cross stitching 7 is applied after the free threads 5 of the patch have been

drawn through the fabric, and may be used either alone, as shown in Figure 8, or in conjunction with the binding stitch 6, as shown in Figure 9. The cross stitching is of fine thread of a high quality, for example, silk giving maximum strength without adding noticeable bulk to the edges of the patch.

Having described my invention, I claim:

1. The method of mending damaged spots in fabrics, consisting in cutting out a damaged area along lines parallel to the warp and woof threads of the fabric, extending a line of stitching marginally around the edges of the opening produced by the cut-out area, applying a patch of the same material of the fabric having a central body portion of a shape conforming to the area surrounded by said line of stitching in the fabric, the patch having its body portion surrounded by free threads constituting loose extensions of the warp and woof threads thereof, drawing the free threads of the patch through the fabric along said line of stitching and at a side outermost from the opening, binding together said loose fibers and margin of the fabric by a line of stitching at the base of the joined parts, removing a portion of the warp and woof threads of said margin, and folding the same with the patch threads down in parallelism with the plane of the fabric.
2. The method of mending damaged spots in fabrics, consisting in cutting out a damaged area along lines parallel to the warp and woof threads of the fabric, applying a patch of the same material of the fabric having a central body portion of a shape conforming to marginally overlap the cut out areas in the fabric, the patch having its body portion surrounded by free threads constituting loose extensions of the warp and woof threads thereof, drawing the free threads of the patch through the fabric, sewing together said loose fibers and margin of the fabric at the base of the joined parts, removing a portion of the warp and woof threads of said margin corresponding with the patch, and folding the same with the patch threads down in parallelism with the plane of the fabric.
3. The method of mending damaged spots in fabrics, consisting in cutting out a damaged area along lines parallel to the warp and woof threads of the fabric, applying a patch of the same material of the fabric having a body portion marginally overlapping the fabric about the cut out area, the patch having its body portion surrounded by free threads constituting loose extensions of the warp and woof threads thereof, drawing the free threads of the patch through the fabric, sewing together said loose fibers and margin of the fabric which the body of the patch overlies, and folding the same to form a hem.
4. The method of mending damaged spots in fabrics, consisting in cutting out a damaged area along lines parallel to the warp and woof threads of the fabric, applying a patch of the same material of the fabric of larger area than the opening over the outer side of the fabric to cover the opening, the patch having its body portion surrounded by free threads constituting loose extensions of the warp and woof threads thereof and drawing the free threads of the patch through the fabric and securing the same to the margin of the fabric which the body portion of the patch overlies, removing a portion of the warp and woof threads of said margin, and folding the same with the patch threads to form a hem.
5. The method of mending damaged spots in

fabrics, consisting in cutting out a damaged area along lines parallel to the warp and woof threads of the fabric, applying a patch of the same material of the fabric having a body portion marginally overlapping the fabric about the cut out area, the patch having its body portion surrounded by free threads constituting loose extensions of the warp and woof threads thereof, drawing the free threads of the patch through the fabric, and binding together the adjoining edges of the patch and fabric by a line of cross stitching marginally about the adjoining parts and concealed within the body of the patch and fabric.

6. The method of mending damaged spots in fabrics, consisting in cutting out a damaged area along lines parallel to the warp and woof threads of the fabric, extending a line of stitching marginally around the edges of the opening produced by the cut out area, applying a patch of the same material of the fabric having a central body portion of a shape conforming to the area surrounded by said line of stitching in the fabric, the patch having its body portion surrounded by free threads constituting loose extensions of the warp and woof threads thereof, drawing the free threads of the patch through the fabric along said line of stitching and at a side outermost from the opening, and binding together the adjoining edges of the patch and fabric by a line of cross stitching marginally about the adjoining parts.

7. The method of mending damaged spots in fabrics, consisting in cutting out a damaged area

5 along lines parallel to the warp and woof threads of the fabric, applying a patch of the same material of the fabric having a central body portion of a shape conforming to marginally overlap the cut out area in the fabric, the patch having its body portion surrounded by free threads constituting loose extensions of the warp and woof threads thereof, drawing the free threads of the patch through the fabric, binding together the adjoining edges of the patch and fabric by a line of cross stitching marginally about the adjoining parts and concealed within the body of the patch and fabric, and sewing together the free threads of the patch and margin of the fabric to form a hem.

10 8. The method of mending damaged spots in fabrics, consisting in cutting out a damaged area along lines parallel to the warp and woof threads of the fabric, extending a line of stitching marginally around the edges of the opening produced by the cut out area, applying a patch of the same material of fabric having a central body portion of a shape conforming to the area surrounded by said line of stitching in the fabric, the patch having a fringed margin produced for each edge by removing the threads extending longitudinally of the edge, drawing the free threads of the fringe of the patch through the fabric along said line of stitching at a side outermost of the opening, and securing said fringed margins to the relative adjoining margins of the fabric about the cut out by stitching the same together at the base of the joined parts.

MARY LOUISE ROACH.
